UNITED STATES PATENT OFFICE

145,781

DESIGN FOR A CHILD'S CHAIR

Frederick L. Duer, Chicago, Ill.

Application January 16, 1946, Serial No. 125,587

Term of patent 14 years

(Cl. D15—1)

To all whom it may concern:

Be it known that I, Frederick L. Duer, a citizen of the United States, residing at Chicago, in the county of Cook and State of Illinois, have invented a new, original, and ornamental Design for a Child's Chair, of which the following is a specification, reference being had to the accompanying drawings, forming part thereof.

In the drawings:

I claim:

The ornamental design for a child's chair, as shown.

FREDERICK L. DUER.
